CLAIM

The ornamental design for an endpoint for a videoconference, as shown and described.

DESCRIPTION

FIG. 1 is a front perspective view of the endpoint for a videoconference embodying our new design.

FIG. 2 is a front perspective view of the endpoint for a videoconference with a panel in the open position.

FIG. 3 is a front view of the endpoint for a videoconference.

FIG. 4 is a right side perspective view of the endpoint for a videoconference.

FIG. 5 is a right side view of the endpoint for a videoconference; and,

FIG. 6 is a back view of the endpoint for a videoconference. The broken lines are shown for illustrative purposes only and form no part of the claimed design.
